THERMODYNAMIC MACHINE

Paul Kollsman, New York, N. Y.

Application August 27, 1945, Serial No. 612,954

16 Claims. (Cl. 62—136)

1

This invention relates to a thermodynamic machine for effecting cooling by passing a gas in a closed system through a compression-expansion cycle with absorption of the heat of compression.

One object of the invention is the provision of a thermodynamic machine in which a gas is rotated while passing in a path radially toward the periphery and return with absorption of the heat of compression of the gas toward the periphery and with cooling effected by the expanding gas in the return path, with the gas from the return portion of the path being returned to the outwardly extending path portion.

Another object of the invention is a thermodynamic machine in accordance with the preceding object in which flow of gas is effected by a centrifugal compressor portion of the machine.

Another object of the invention is a thermodynamic machine in accordance with the preceding objects in which there is provided heat transfer means for further cooling the compressed gas by the lower temperature expanded gas after leaving its heat exchange portion.

Other objects and features of the invention will be readily apparent to those skilled in the art from the specification and appended drawings illustrating certain preferred embodiments in which:

Figure 1 is a view partially in section and partly in elevation of a thermodynamic machine according to the present invention.

Figure 2 is a view partly in section on the line II—II of Figure 1 with the lower portion shown in elevation.

Figure 3 is a partial sectional view on the line III—III of Figure 1.

Figure 4 is a reduced partial sectional view on the line IV—IV of Figure 1.

As specifically illustrated in the drawings the thermodynamic machine according to the present invention comprises an outer casing 1 within which is rotatably supported a shaft 2 upon a direct bearing 3 and an indirect bearing 4 in which rotates a part rigid with the shaft. Upon the shaft 2 is mounted an interior rotor portion 5 formed of spaced sections to provide an insulating space 6, with the space adjacent the axis of the machine filled by a solid insulating seal 7. Externally of the interior rotor section 5 is an outer casing 6' connected thereto by a plurality of fins 7 spaced circumferentially about the rotor to form a plurality of individual gas chambers having radial legs 8 and 9 and a peripheral bight 11. The chambers further comprise axially extending portions 12 provided by fins 13 be-

2

tween shaft 2 and the interior rotor section 5. A hub 14 connected to the casing 6' is received within the bearing 4 to complete the support for the rotor elements.

At the inner end of the shaft 2 there is provided a disc 15 rotating therewith and connected to the interior rotor portion by radially extending portions 16 of the fins 13 so as to form a plurality of short radially extending chamber legs 17. Outwardly of the ends of the chamber legs 17 there is provided a diffuser passage 18 between disc 15 and the inner rotor portion 5.

Rigidly mounted in the hub of the casing 1 is a stationary shaft 19 carrying a stationary disc 21 upon which are supported a plurality of fins 22 forming stationary chamber legs 23. The rotary chamber legs 8 and 9 and their connecting peripheral bights 11, with the axially extending legs 12 and the short radially extending legs 17 form a plurality of continuous gas passages spaced circumferentially about the rotor. These passages communicate with the common diffuser passage 18 and again with the individual stationary chamber legs 23 likewise forming a plurality of individual chambers spaced circumferentially about the rotor.

Within the casing 1, adjacent the chamber leg 8 and a portion of the chamber bight 11 there is disposed a sprayer 24 for cooling water to be sprayed on the exterior of casing 6' to absorb the heat of compression of the gas within the passages about the rotor. The casing 6' is shown of relatively thin section to facilitate heat transfer and is preferably formed of a material effecting heat transfer with high efficiency. The cooling water is drawn off from the casing through the outlet 25. Along the chamber leg 9 there is shown a heat transfer medium comprising a sprayer 26 for spraying a liquid on the surface of the casing 6' so as to effect a reduction of the temperature of the liquid with the liquid discharged through the outlet 27 to supply a usable cooled medium.

Within the interior of rotor 5 there are provided a plurality of closed passageways 28 spaced circumferentially about the rotor and preferably with at least one passageway provided for each chamber about the rotor. Within the passageways 28 there is provided a liquid adapted to circulate under the action of centrifugal force on different temperature and density portions of the liquid with the interior axially extending legs of the passageways in heat transfer relation with the chamber legs 12 and with the peripheral axially extending legs of the passageways in heat

transfer relation with the chamber bights 11. The gas in the passages in the machine is preferably a heavy gas maintained at superatmospheric pressure. One of the monatomic gases is particularly suited for this purpose although the machine will function with the use of any gas therein.

While certain of the passage or chamber legs have been spoken of as radial, it will be understood that they may have any desired direction having radial components.

In operation of the machine the shaft 2 is rotated from an exterior source of power and cooling water is supplied to the wall of casing 6' from the sprayer 26. As the rotor elements are rotated, the short radially extending chamber legs 17 act as a centrifugal compressor to force gas outwardly from their periphery into the diffuser passage 18. Within the passage 18 the rotational energy of the gas is converted into pressure energy to effect a resultant flow of gas through the passages or chambers about the rotor. Gas passing inwardly through the chamber legs 23 has no rotational velocity since the fins 22 are stationary so that no back-pressure is built up to oppose the pressure obtained from the chamber legs 17. Gas leaving the stationary chamber legs 23 enters the rotary chamber legs or passages 8 and moves outwardly toward the periphery of the machine. As the gas passes toward the bights 11 of the chambers it becomes progressively compressed under the action of centrifugal force on the gas columns in the radial chamber legs 8 and 9 and the heat of compression of the gas is absorbed by the cooling water from the sprayer 24 contracting the outer surface of the casing 6' bounding the gas passages. As the gas moves inwardly toward the axis of the machine through the chamber legs 9, it will progressively expand with a resultant lowering of temperature and with heat transfer through the walls of casing 6' to cool the liquid from the sprayer 26. The gas passing into the axially extending chamber legs 12 will be at a lower temperature than the compressed gas and will cool the liquid in the inner axially extending leg of the passageway 28. Under the action of centrifugal force on the different density and temperature portions of the liquid in the passageway 28, a circulating flow will be set up in a counterclockwise direction as viewed in Figure 1. As the cooled liquid reaches the axially extending leg of the passageway adjacent to the periphery of the rotor, it will absorb heat from the compressed gas within chamber bights 11 to further lower the temperature of the compressed gas. It will be noted that the liquid circulation is in counterflow relation with the flow of gas through the axially extending passages or chambers 11 and 12. With the circulating heat exchanger the temperature of the compressed gas is lowered to provide for a further lowering of the temperature of the expanding gas in the chamber legs 9 or for a greater heat absorption thereat.

The interior of the casing 1 is evacuated through the outlet 29 to lessen the air frictional resistance to rotation of the casing 6'. The casing 1 may, alternatively, be filled with a light gas, such as hydrogen or helium, to reduce the resistance to rotation of the casing.

Since the gas in the chamber legs 9 is at a lower temperature than that in the chamber legs 8, the action of centrifugal force thereon tends to oppose the passage of gas in the desired direction through the passages or chambers and this

force must be overcome by the pressure developed by the rotary compressor formed by the chamber legs 17 to effect the desired flow.

While the machine has been described for effecting cooling of the medium introduced through sprayer 26 it will be understood that it may also be used to effect heating of the medium introduced from the sprayer 24 with the fluid from the sprayer 26 utilized to heat the gas in the expansion passages. For this utilization the function of the sprayers may be reversed with water at normal temperature introduced from the sprayer 26 and the medium to be heated introduced from the sprayer 24.

While certain preferred embodiments of the invention have been specifically disclosed, it is understood that the invention is not limited thereto, as many variations will be readily apparent to those skilled in the art and the invention is to be given its broadest possible interpretation within the terms of the following claims:

What is claimed is:

1. In a thermodynamic machine, means providing a substantial U-shaped passage for gas flow, means for rotating said first mentioned means about an axis with the legs of the U extending substantially radially of the axis and with the bight remote therefrom, the gas in said passage being progressively compressed toward the bight under the action of centrifugal force on the gas columns in the legs, means for absorbing the heat of compression of the compressed gas, means interconnecting the ends of said legs including pump means for effecting a continuous flow of gas through said passage, and means introducing a medium to be cooled in heat transfer relation with the expanding gas in the outlet leg of the passage.

2. In a thermodynamic machine, means providing a substantially U-shaped passage for gas flow, means for rotating said first mentioned means about an axis with the legs of the U extending substantially radially of the axis and with the bight remote therefrom, the gas in said passage being progressively compressed toward the bight under the action of centrifugal force on the gas columns in the legs, means for absorbing the heat of compression of the compressed gas, means interconnecting the ends of said passage to form a closed system, said interconnecting means comprising a gas passage rotating with the said first mentioned means to form a centrifugal compressor to maintain the flow of gas through said passage, and means for introducing a medium to be cooled in heat transfer relation with the expanding gas.

3. In a thermodynamic machine, means providing a substantially U-shaped passage for gas flow, means for rotating said first mentioned means about an axis with the legs of the U extending substantially radially of the axis and with the bight remote therefrom, the gas in said passage being progressively compressed toward the bight under the action of centrifugal force on the gas columns in the legs, means for absorbing the heat of compression of the compressed gas, means interconnecting the ends of said passage to form a closed system, said interconnecting means comprising a gas passage rotating with the said first

60 means to form a centrifugal compressor, and a stationary passage leading from said compressor to the inlet leg of the U for maintaining gas flow through the passage.

4. In a thermodynamic machine, means providing a substantially U-shaped passage for gas

flow, means for rotating said first mentioned means about an axis with the legs of the U extending substantially radially of the axis and with the bight remote therefrom, the gas in said passage being progressively compressed toward the bight under the action of centrifugal force on the gas columns in the legs, means for absorbing the heat of compression of the compressed gas, means interconnecting the ends of said passage to form a closed system, said interconnecting means comprising a gas passage rotating with the said first mentioned means to form a centrifugal compressor and a stationary passage leading from said compressor to the inlet leg of the U for maintaining gas flow through the passage, and means for introducing a medium to be cooled in heat transfer relation with the expanding gas in the passage.

5. In a thermodynamic machine, means providing a substantially U-shaped passage for gas flow, means for rotating said first mentioned means about an axis with the legs of the U extending substantially radially of the axis and with the bight remote therefrom, the gas in said passage being progressively compressed toward the bight under the action of centrifugal force on the gas columns in the legs, means for absorbing the heat of compression of the compressed gas, means interconnecting the ends of said passage to form a closed system, said interconnecting means comprising a gas passage rotating with the said first mentioned means to form a centrifugal compressor and a stationary passage leading from said compressor to the inlet leg of the U for maintaining gas flow through the passage, means for introducing a medium to be cooled in heat transfer relation with the expanding gas in the passage, and means for further cooling the compressed gas by the residual low temperature of the expanded gas after absorption of heat from said medium to be cooled.

6. In a thermodynamic machine, means providing a substantially U-shaped passage for gas flow, means for rotating said first mentioned means about an axis with the legs of the U extending substantially radially of the axis and with the bight remote therefrom, the gas in said passage being progressively compressed toward the bight under the action of centrifugal force on the gas columns in the legs, means for absorbing the heat of compression of the compressed gas, means for effecting gas flow through said passage, means for introducing a medium to be cooled in heat transfer relation with the expanding gas in the outlet leg of the passage, and means for further cooling the compressed gas by the residual low temperature of the expanded gas after absorption of heat from said medium to be cooled.

7. In a thermodynamic machine, means providing a substantially U-shaped passage for gas flow, means for rotating said first mentioned means about an axis with the legs of the U extending substantially radially of the axis and with the bight remote therefrom, the gas in said passage being progressively compressed toward the bight under the action of centrifugal force on the gas columns in the legs, means for absorbing the heat of compression of the compressed gas, means for effecting gas flow through said passage, means for introducing a medium to be cooled in heat transfer relation with the expanding gas in the outlet leg of the passage, and means for further cooling the compressed gas by the residual low temperature of the expanded gas

after absorption of heat from said medium to be cooled, including a liquid circulating in counter flow heat exchange relation with the expanded and compressed gas.

8. In a thermodynamic machine, means providing a substantially U-shaped passage for gas flow, means for rotating said first mentioned means about an axis with the legs of the U extending substantially radially of the axis and with the bight remote therefrom, the gas in said passage being progressively compressed toward the bight under the action of centrifugal force on the gas columns in the legs, means for absorbing the heat of compression of the compressed gas, means for effecting gas flow through said passage, means for introducing a medium to be cooled in heat transfer relation with the expanding gas in the outlet leg of the passage, and means for further cooling the compressed gas by the residual low temperature of the expanded gas after absorption of heat from said medium to be cooled including a liquid circulating in counter flow heat exchange relation with the expanded and compressed gas, the liquid circulation being maintained by the action of centrifugal force on portions thereof at different temperature and density.

9. In a thermodynamic machine, a rotor, a plurality of individual gas chambers spaced circumferentially about said rotor, said chambers having radially extending portions and peripheral connecting bights, passage means within the rotor interconnecting the ends of said chambers for forming a closed system, means for rotating said rotor from a power source, the gas in said radial legs being progressively compressed toward the peripheral bights under the action of centrifugal force on the gas columns in the legs, means for absorbing the heat of compression of the compressed gas, means for effecting gas flow through said chambers, and means including a duct separate from said chambers and passage means for introducing a medium to be cooled in heat transfer relation with the expanding gas flowing toward the axis of the rotor.

45. 10. In a thermodynamic machine, a rotor, a plurality of individual gas chambers spaced circumferentially about said rotor, said chambers having radially extending portions and peripheral connecting bights, passage means interconnecting the ends of said chambers for forming a closed system, means for rotating said rotor from an exterior power source, the gas in said radial legs being progressively compressed toward the peripheral bights under the action of centrifugal force on the gas columns in the legs, means for absorbing the heat of compression of the compressed gas, means for effecting gas flow through said chambers, means for introducing a medium to be cooled in heat transfer relation with the expanding gas flowing toward the axis of the rotor and means for further cooling the compressed gas adjacent the bights of the chambers by the residual low temperature of the expanded gas after heat absorption from said medium to be cooled.

11. In a thermodynamic machine, a rotor, a plurality of individual gas chambers spaced circumferentially about said rotor, said chambers having radially extending portions forming legs and peripheral connecting bights, the ends of one set of the legs of said chambers constituting outlets, and having axially extending portions, a rotary compressor within said rotor communicating with said axial portions for delivering the

gas to the ends of the other chamber legs constituting inlets to effect a continuous closed gas flow through the chambers, means for absorbing the heat of compression of the compressed gas, and means including a duct separate from said chambers and legs for introducing a medium to be cooled in heat transfer relation with the expanded gas circulating within the rotor.

12. In a thermodynamic machine, a rotor, a plurality of individual gas chambers spaced circumferentially about said rotor, said chambers having radially extending portions forming legs and peripheral connecting bights, the ends of one set of the legs of said chambers constituting outlets and having axially extending portions, a rotary compressor within said rotor for delivering the gas from said outlets to the ends of the other chamber legs constituting inlets to effect a continuous closed gas flow through the chambers, said compressor including a common diffuser passage wherein the rotational energy imparted to the gas by the compressor is converted into pressure energy to effect gas flow, the gas from said diffuser being led to the inlet ends of the other set of chamber legs without rotational energy, means for absorbing the heat of the compressed gas, and means including a duct separate from said chamber and legs for introducing a medium to be cooled in heat transfer relation with the expanded gas.

13. In a thermodynamic machine, a rotor, a plurality of individual gas chambers spaced circumferentially about said rotor, said chambers having radially extending portions forming legs and peripheral connecting bights; the ends of one set of the legs of said chambers constituting outlets and having axially extending portions, a rotary compressor within said rotor for delivering the gas from said outlets to the ends of the other chamber legs constituting inlets to effect a continuous closed gas flow through the chambers, said compressor including a common diffuser passage wherein the rotational energy imparted to the gas by the compressor is converted into pressure energy to effect gas flow, the gas from said diffuser being led to the inlet ends of the other set of chamber legs, means for absorbing the heat of compression of the compressed gas, means including a duct separate from said chamber and legs for introducing a medium to be cooled in heat transfer relation with the expanding gas, and means for further cooling the compressed gas by the residual low temperature of the expanding gas after heat absorption from said medium to be cooled.

14. In a thermodynamic machine, a rotor, a plurality of individual gas chambers spaced circumferentially about said rotor, said chambers having radially extending portions forming legs and peripheral connecting bights, the ends of one set of the legs of said chambers constituting outlets and having axially extending portions, a rotary compressor within said rotor for delivering the gas from said outlets to the ends of the

other chamber legs to effect a continuous closed gas flow through the chambers, said compressor including a diffuser passage common to said chambers wherein rotational energy imparted to the gas is converted into pressure energy, a plurality of stationary passages leading from said diffuser into the inlet ends of said other set of chamber legs, means for absorbing the heat of compression of the compressed gas, and means including a duct separate from said chambers and legs for introducing a fluid to be cooled in heat transfer relation with the expanded gas.

15. In a thermodynamic machine, a rotor, a plurality of individual gas chambers spaced circumferentially about said rotor, said chambers having radially extending portions and peripheral connecting bights, passage means interconnecting the ends of said chambers for forming a closed system, means for rotating said rotor from an exterior power source, the gas in said radial chamber legs being progressively compressed toward the peripheral bights under the action of centrifugal force on the gas columns in the legs, means for absorbing the heat of compression of the compressed gas, means for effecting gas flow through said chambers, means for introducing a medium to be cooled in heat transfer relation with the expanding gas flowing toward the axis of the rotor, and means establishing a vacuum in the space about said rotor to reduce air frictional losses incident to its rotation.

16. In a thermodynamic machine, a rotor, a plurality of individual gas chambers spaced circumferentially about said rotor, said chambers having radially extending portions and peripheral connecting bights, passage means interconnecting the ends of said chambers to form a closed system, means for rotating said rotor from an exterior power source, the gas in said radial legs being progressively compressed toward the peripheral bights under the action of centrifugal force on the gas columns in the legs, means for absorbing the heat of compression of the compressed gas, means for effecting gas flow through said chambers, means for introducing a medium to be cooled in heat transfer relation with the expanding gas flowing toward the axis of the rotor, and a closed stationary casing about said rotor, the space between said casing and rotor being filled with low density gas to reduce air friction at the exterior surface of the rotor.
